UNITED STATES PATENT OFFICE.

HENRY E. VAN NESS, OF ELMIRA, NEW YORK, ASSIGNOR TO ECLIPSE MACHINE COMPANY, OF ELMIRA, NEW YORK, A CORPORATION OF NEW YORK.

ENGINE-STARTER.

1,288,767.

Specification of Letters Patent. Patented Dec. 24, 1918.

Application filed March 9, 1917. Serial No. 153,700.

To all whom it may concern:

Be it known that I, HENRY E. VAN NESS, a citizen of the United States, residing at Elmira, in the county of Chemung and State 5 of New York, have invented certain new and useful Improvements in Engine-Starters, of which the following is a specification.

My invention relates to that type of engine starter exemplified in patents heretofore issued to Vincent Bendix, for instance, Patents No. 1,125,935, dated January 26, 1915, and No. 1,172,864, dated February 22, 1916, which starters are characterized by a prime mover such as an electric motor, and a transmission or drive for transmitting the power of the motor by means of a rotatable screw shaft and a pinion mounted thereon, to a member of the engine to be started, such as the fly wheel thereof. This drive comprises 15 a screw shaft operated either directly or indirectly by the motor and a pinion screw-threaded on such shaft and having longitudinal movement thereon and rotary movement therewith.

In this type of drive or transmission there is a slight longitudinal yielding movement of the screw shaft for the purpose explained in said Patent No. 1,125,935, there being a compression space provided between the end 25 of the shaft and a collar or spring barrel which space is indicated at 9 in said patent. The object of my invention is to provide simple and efficient means for preventing any possibility of the coiled spring which forms 30 the resilient driving connection dropping or wedging into said space.

In the drawing Figure 1 is an elevation partly in section illustrating a drive embodying my invention; Figs. 2 and 3 cross-sections on the line 2—2 of Fig. 1 but looking in opposite directions as indicated by the arrows; Fig. 4 a view similar to Fig. 1 but illustrating a modified form of construction; Fig. 5 an end elevation of the outer end of 45 the screw shaft, and Fig. 6 a detail sectional view of the engaging members 7 and 10.

Referring to the embodiment of my invention as herein shown, the drive comprises a hollow screw shaft 1 driven by the extended 50 armature shaft 2 of a starting motor indicated at 3, a pinion 4 screw-threaded on the screw shaft and adapted to mesh or engage with a rotatable part of the engine to be started, such as the teeth 5^a of the fly wheel 5. 55 The armature shaft passes axially through

the screw shaft and has fastened to its outer end by means of a bolt 6 a collar 7. The power of the motor is transmitted to the screw shaft by a resilient driving connection consisting of a coiled spring 8, one end of 60 which is secured to the bolt 6 and the other end to the bolt or stud 9 screwing into an enlargement or collar portion 1^a of the screw shaft. A sleeve 10 is arranged within the coils of the spring and encircles the outer 65 plain portion of the screw shaft at a point between said collar portion 1^a and the collar 7, such sleeve being mounted directly on the motor shaft 2 in abutting relation as to one end with said collar portion 1^a of the threaded sleeve and coöperating at the other end with said collar 7. This sleeve is diametrically slotted or cut back from its outer end, thereby leaving on opposite sides two similar arc-shaped extensions 10^a. The slots thus 70 formed in this sleeve receive complementary arc-shaped extensions 7^a of the collar 7, which at diametrically opposite sides is cut away in order to accommodate the extensions 75 10^a of the sleeve 10. As a result the sleeve 80 and collar are adapted to slide longitudinally upon each other in the operation of the device, but to always present surfaces which may be contacted by the spring coils and be thereby prevented from falling into any 85 open space.

The proper position of the sleeve 10 is inwardly toward the collar 1^a. In order that the same may be retained in such position springs 11 are interposed between such sleeve 90 and the collar 7. According to the construction in Fig. 1 these springs are received in longitudinal sockets 12 in the body portion of the sleeve and are therefore adapted to bear against the extensions 7^a of the collar. 95 In the construction shown in Fig. 4 the springs are received in sockets 13 in the extensions 10^a of the sleeve and also in sockets 14 in the body portion of the collar 7.

The screw shaft and pinion are capable of 100 a yielding longitudinal movement upon the screw shaft which occurs in the event that the pinion teeth should meet the fly wheel teeth end to end and consequently this sliding movement of the sleeve with respect to the collar is necessary. This sleeve and collar provide support for the spring 8 in case it should be coiled inwardly upon such sleeve and collar, and leaves no space into which any coil of the spring could drop or wedge. 110

At the same time the desired longitudinal yielding movement of the screw shaft is permitted without any interference.

I claim:

- 5 1. A starter for engines comprising a rotatable member, a driving member, a coiled spring connecting between said members and forming a resilient driving connection therefor, and members arranged within the coils 10 of said spring, the adjacent ends of such latter members being formed with complementary and coöperating diametrical recesses and extensions.
  - 15 2. A starter for engines comprising a rotatable screw shaft, a driving shaft, a coiled spring connecting between the shafts and forming a resilient driving connection, and two members slidably engaging each other and encircling the screw shaft within the 20 spring coils, the adjacent ends of such members being formed with complementary diametrical recesses and extensions.
  - 25 3. A starter for engines comprising a rotatable screw shaft, a driving shaft, a coiled spring connecting between the shafts and forming a resilient driving connection, and two members slidably engaging each other and encircling the screw shaft within the 30 spring coils, the adjacent ends of such members being formed with complementary diametrical recesses and extensions and springs interposed between such ends of the members for normally holding them in extended condition.
  - 35 4. A starter for engines comprising a rotatable screw shaft, a driving shaft, a coiled spring connecting between the shafts and forming a resilient driving connection, and two members encircling the screw shaft within the 40 spring coils, the adjacent ends of such members being formed with complementary diametrical recesses and extensions and coiled springs interposed between such ends of the members for normally holding them in extended condition, said members having 45 sockets to receive the ends of said coiled springs.
  5. A starter for engines comprising a rotatable screw shaft, a driving shaft, a coiled
- spring connecting between the shafts and 50 forming a resilient driving connection and two members encircling the screw shaft within the spring coils, the adjacent ends of such members being formed with complementary diametrical recesses and extensions, 55 one of said members having a pair of diametrical extensions and the other thereof having a pair of diametrical recesses receiving such extensions.
6. A starter for engines comprising a rotatable screw shaft, a driving shaft, a coiled spring connecting between the shafts and forming a resilient driving connection, and two members encircling the screw shaft within the spring coils, the adjacent ends of 60 such members being formed with complementary diametrical recesses and extensions, one of said members having a pair of diametrical extensions and the other thereof having a pair of diametrical recesses receiving such extensions, and springs interposed between said two members for normally holding them in extended condition.
7. A starter for engines comprising a rotatable screw shaft, a driving shaft, a collar secured to the driving shaft and having a pair of diametrical extensions and recesses, 75 a sleeve surrounding one end of the screw shaft and having a pair of diametrical extensions and also recesses receiving such extensions, and a coiled spring surrounding such sleeve and collar and connected at its ends to the screw shaft and collar.
8. A starter for engines comprising a rotatable screw shaft, a driving shaft, a collar secured to the driving shaft and having a pair of diametrical extensions and recesses, 80 a sleeve surrounding one end of the screw shaft and having a pair of diametrical extensions and also recesses receiving such extensions, 85 a coiled spring surrounding such sleeve and collar and connected at its ends to the screw shaft and collar, and springs interposed between the extensions of one member and the bottom of the recesses of the 90 other member.
- 95

HENRY E. VAN NESS.
